EARLD H. LAMIELL, OF CANTON, OHIO, ASSIGNOR TO THE H. L. HURST MANUFACTURING COMPANY, OF CANTON, OHIO, A CORPORATION OF OHIO.

ADJUSTABLE SPRAY-NOZZLE.

1,079,131.

Specification of Letters Patent. Patented Nov. 18, 1913.

Application filed June 17, 1912. Serial No. 704,003.

To all whom it may concern:

Be it known that I, EARLD H. LAMIELL, a citizen of the United States, residing at Canton, in the county of Stark and State of Ohio, have invented a new and useful Adjustable Spray-Nozzle, of which the following is a specification.

My invention relates to improvements in spray nozzles, and while applicable to many uses is peculiarly adapted for use in spraying insecticides and fungicides.

The objects of the invention are to provide a simple spray nozzle for the purpose indicated, which is adjustable, making it possible by adjustment to throw a spray or a stream from the nozzle, as the operator may desire, the adjustment being made without discontinuing the spraying and without the necessity of the operator leaving his accustomed position.

A further important object is to provide for the quick and convenient clearing of the spraying aperture when same becomes clogged by forcing therethrough a full stream of spraying liquid.

These objects, together with other objects apparent to those skilled in the art, may be attained by the construction illustrated in the accompanying drawings, although the invention may be embodied in other forms, the construction illustrated being chosen by way of example.

In the drawings Figure 1 is a perspective view of a spray nozzle embodying my invention mounted upon an extension tube. Fig. 2 is a longitudinal sectional view through a nozzle embodying my invention, the parts being shown in the spraying position. Fig. 3 is a similar view showing the parts, however, in the solid-stream position. Fig. 4 is a front face view of the vortex-head. Fig. 5 is a longitudinal sectional view of the parts comprising the nozzle separated from each other. The sections shown in Figs. 2, 3 and 5 are taken on the line $\alpha-\alpha$ shown on Fig. 4, looking in the direction of the arrows there shown.

Throughout the several views similar reference numerals indicate similar parts.

More specifically describing the construction disclosed in said drawings the numeral 1 indicates an inflexible extension tube, the lower end 2 of which should be connected, as by a flexible hose, to a source of spraying liquid under pressure. Said tube is prefer-

ably made of metal and is of any length desired, from a few inches to many feet. On the upper end of said tube is mounted the spraying nozzle. The spraying nozzle comprises a vortex thimble provided with the hollow cylindrical body 3 and the integral vortex head 4. Said vortex head is in the form of a disk having a greater diameter than the body 3, the outer edge 5 of the disk thus projecting beyond the cylindrical walls 6 of the body 3 and forming the annular shoulder 6. The end of the body 3 opposite the head 4 is provided with internal screw threads 7 for attaching said body to the tube 1, which should be provided at its upper end with corresponding external screw threads. The head 4 is provided with the inclined vortex-producing apertures 8 arranged in the well known manner so as to direct vortex-producing streams into the nozzle cap. In the walls of the body 3 immediately back of the shoulder 6 are arranged a plurality of radially disposed auxiliary apertures 9 for the purpose herein-after to be explained. Longitudinally slidably mounted upon the body 3 is the cap retaining ring 10 provided at its forward end with an annular, externally screw threaded projection 11 of somewhat greater diameter than the head 4. The back end of the retaining ring is preferably externally reduced and provided with the external screw threads 12 adapted to receive the internal screw threads 13 of the packing ring 14 which is provided with an inwardly disposed, annular packing-retaining flange 15 extending into close relation to the outer surface of the body 3 and adapted to hold the packing 16 in position between the end of the ring 10 and said flange, said packing being adapted to slidably engage the body 3, as will be apparent from an inspection of Figs. 2 and 3.

The nozzle cap is provided with the cylindrical side walls 17 provided internally at the rear with screw threads 18 adapted to engage the external screw threads on the projection 11. The head 19 closes the front end of the cap except for a small central spraying aperture 20, and the front face of the head 19 is preferably concave, in the manner common in the art. It should be noted that the length of the walls 17 is such that when the cap is connected to the retaining ring 10, as shown in Fig. 2, and said retain-

ing ring 10 engages the shoulder 6 there will be sufficient space between the head 4 and the head 19 to produce the necessary whirl or vortex to cause a spray to issue from the 5 aperture 20. It should also be noted that the internal diameter of the cap is greater than the diameter of the head 4 so that there is a space between the outer edge 5 of the head and the inner sides of the walls 17.

10 The various parts, as described, having been assembled and connected to the tube 1, when fluid under pressure is forced through said tube into the nozzle the pressure of the fluid against the head 19 will cause the ring 15 10 to slide forwardly on the body 3 until said ring engages the shoulder 6. In such position, illustrated in Fig. 2, the auxiliary apertures 9 will be closed by reason of the ring 10 overlying the same, and the liquid being 20 directed into the nozzle cap through the vortex-producing apertures 8 only will be caused to whirl within said cap and produce a spray issuing from the aperture 20. Should the aperture 20 become clogged and 25 it be desired to clear the same, or should it be desired to direct a solid stream from the aperture 20, for any reason, as for reaching a distant point or applying an unusual quantity of spraying liquid, the ring 10 together with the cap should be drawn back 30 with relation to the body 3, and against the force of the liquid in the cap until the auxiliary apertures 9 are uncovered by the receding ring 10, as illustrated in Fig. 3. As 35 soon as said apertures are uncovered liquid will be directed through said apertures in radial directions against the side walls 17 and thence around the edge 5 of the head 4 into the front portion of the cap, thus destroying the whirling action of the liquid within said cap, producing a solid "head" of liquid within said cap, and causing a solid stream of liquid to be directed through the aperture 20.

40 45 It will be understood that in the practical use of the invention the nozzle is desired in the spraying adjustment the greater portion of the time and that the throwing of a solid stream is desired only occasionally. If 50 it is desired to throw a solid stream only for the purpose of clearing the aperture 20 it may be most convenient to slide the ring 10 back upon the body 3 by bringing the cap of the nozzle into engagement with some object, 55 as for instance the limb of a tree, and pushing forwardly upon the tube 1, or if the nozzle is connected directly to the flexible hose for short-range work the ring 10 may be moved back by the hand. In the spraying 60 of trees and shrubbery, however, it will be understood that it is frequently necessary to use an extension tube of considerable length and it may also be more frequently desirable to direct a solid stream from the nozzle. For 65 the purpose of conveniently adjusting the

nozzle from the lower end of the tube 1, therefore, a connecting wire 21 may be attached to the packing ring 14 in any mechanical manner, said wire extending along the tube 1 to a point within convenient reach 70 of the operator, where the lower end of the wire may be connected as at 22 to a bell-crank-shaped thumb lever having the spaced arms 23 pivotally connected to the two sides of the tube 1, and a thumb lever portion 24 75 extending rearwardly. It will be apparent from an inspection of Fig. 1 that the operator by placing his thumb upon the lever 24 and pressing the same down into engagement with the tube 1 will draw the connection at 22 rearwardly, thus pulling on the wire 21 and bringing the nozzle into the solid-stream adjustment shown in Fig. 3. When the pressure upon the lever 24 is released the force of the liquid within the nozzle cap will move the ring 10 and nozzle cap forwardly, thus automatically restoring the nozzle to the spraying adjustment. 85

It will thus be seen that, generally speaking, my invention may be said to consist of 90 a stationary member, comprising the body 3 with the head 4 and a movable member, including the nozzle cap and the ring 10, the packing ring 14 and packing 16 being a detail of relative unimportance, and that 95 numerous changes in the form and construction of the device may be resorted to as circumstances may require or experience suggest without departing from the spirit of the invention or the scope of the appended 100 claims.

I claim:—

1. A spray nozzle comprising a hollow, stationary member provided with means for connection to a spraying-liquid supply pipe 105 and provided with vortex-producing apertures and auxiliary apertures, and a movable member connected to said stationary member, said movable member provided with a hollow cap having a spring aperture, 110 said movable member adapted for forward and backward sliding movement with relation to said stationary member and adapted to close said auxiliary apertures when in the forward position and to uncover said apertures when in the rear position. 115

2. A spray nozzle comprising a stationary member provided with a hollow cylindrical body and a vortex head, said vortex head provided with inclined vortex-producing 120 apertures, and the cylindrical walls of said body provided with auxiliary apertures, and a movable member including a hollow cap slidably connected to said body and provided with a spraying aperture, said vortex-producing apertures and auxiliary apertures opening into the interior of said cap, and said movable body adapted to be slidably moved with relation to said stationary body 125 to open and close said auxiliary apertures. 130

3. A spray nozzle comprising a stationary member formed of a hollow cylindrical body provided with a vortex head, said vortex head provided with inclined vortex-producing apertures and the cylindrical walls of said body provided with radially disposed auxiliary apertures, a cap retaining ring slidably mounted upon said cylindrical body and adapted for sliding movement thereon into positions to cover and to uncover said auxiliary apertures, and a hollow cap connected to said ring, inclosing said vortex head, and provided with a spraying aperture.
- 10 4. A spray nozzle comprising a stationary member formed of a hollow cylindrical body provided with a vortex head of greater diameter than said cylindrical body and extending beyond said walls to form an annular shoulder, vortex-producing apertures in said vortex head, auxiliary apertures in the cylindrical walls of said body adjacent said annular shoulder, and a movable member comprising a cap retaining ring longitudinally slidably mounted upon said cylindrical body and a hollow cap connected to said ring, inclosing said vortex head, and provided with a spraying aperture, said cap re-
- 15 taining ring adapted when slidably moved into engagement with said annular shoulder to cover and close said auxiliary apertures, and adapted when slidably moved from said shoulder to uncover and open said apertures.
- 20 5. A spray nozzle comprising a hollow cylindrical member provided with a vortex head having vortex-producing apertures therein, said head of greater diameter than said cylindrical body and extending beyond the outer walls thereof to form an annular shoulder, a hollow cap connected to said cylindrical body, inclosing said vortex head, and provided with a spraying aperture, said cap of greater interior diameter than said vortex head, means for directing streams of spraying liquid into the interior of said cap to the rear of said shoulder, and means for cutting off the flow of said streams.
- 25 In testimony that I claim the above, I have hereunto subscribed my name in the presence of two witnesses.

Correction in Letters Patent No. 1,079,131.

It is hereby certified that in Letters Patent No. 1,079,131, granted November 18, 1913, upon the application of Earld H. Lamiell, of Canton, Ohio, for an improvement in "Adjustable Spray-Nozzles," an error appears in the printed specification requiring correction as follows: Page 2, line 110, for the word "spring" read *spray*; and that the said Letters Patent should be read with this correction therein that the same may conform to the record of the case in the Patent Office.

Signed and sealed this 9th day of December, A. D., 1913.

J. T. NEWTON,

Acting Commissioner of Patents.

3. A spray nozzle comprising a stationary member formed of a hollow cylindrical body provided with a vortex head, said vortex head provided with inclined vortex-producing apertures and the cylindrical walls of said body provided with radially disposed auxiliary apertures, a cap retaining ring slidably mounted upon said cylindrical body and adapted for sliding movement thereon into positions to cover and to uncover said auxiliary apertures, and a hollow cap connected to said ring, inclosing said vortex head, and provided with a spraying aperture.
- 10 4. A spray nozzle comprising a stationary member formed of a hollow cylindrical body provided with a vortex head of greater diameter than said cylindrical body and extending beyond said walls to form an annular shoulder, vortex-producing apertures in said vortex head, auxiliary apertures in the cylindrical walls of said body adjacent said annular shoulder, and a movable member comprising a cap retaining ring longitudinally slidably mounted upon said cylindrical body and a hollow cap connected to said ring, inclosing said vortex head, and provided with a spraying aperture, said cap re-
- 15 taining ring adapted when slidably moved into engagement with said annular shoulder to cover and close said auxiliary apertures, and adapted when slidably moved from said shoulder to uncover and open said apertures.
- 20 5. A spray nozzle comprising a hollow cylindrical member provided with a vortex head having vortex-producing apertures therein, said head of greater diameter than said cylindrical body and extending beyond the outer walls thereof to form an annular shoulder, a hollow cap connected to said cylindrical body, inclosing said vortex head, and provided with a spraying aperture, said cap of greater interior diameter than said vortex head, means for directing streams of spraying liquid into the interior of said cap to the rear of said shoulder, and means for cutting off the flow of said streams.
- 25 In testimony that I claim the above, I have hereunto subscribed my name in the presence of two witnesses.
